EDWARD LUX AND JOSEPH W. DOBBINS, OF SAN DIEGO, CALIFORNIA, ASSIGNEES OF
ONE-FOURTH TO MERRITT G. GORDON AND ONE-FOURTH TO THOMAS H. COLE,
BOTH OF LOS ANGELES, CALIFORNIA.

SANDWICH PREPARING, DISPLAYING, AND VENDING MACHINE.

Application filed May 9, 1922. Serial No. 559,644.

To all whom it may concern:

Be it known that EDWARD LUX and JOSEPH W. DOBBINS, citizens of the United States, residing at San Diego, in the county 5 of San Diego and State of California, have invented a certain new and useful Sandwich Preparing, Displaying, and Vending Machine, of which the following is a specification.

- 10 Our invention relates to food preparing, displaying and vending machines more particularly to machines of this class for automatically preparing, displaying and vending sandwiches and the objects of our invention
15 are: first, to provide a machine of this class which will prepare and deliver sandwiches mechanically and in a sanitary manner; second, to provide a machine of this class in which the food stuffs for making the sandwiches are encased in a transparent enclosure 20 permitting the same to be visible at all times to the public; third, to provide a machine of this class in which the various operations in making the sandwiches may readily be seen; fourth, to provide a machine of this class in which the food stuffs are encased to prevent dust, flies, bugs and other deleterious matter 25 contaminating the same; fifth, to provide an automatic machine for preparing, displaying and vending sandwiches; sixth, to provide a machine of this class which will make 30 different kinds of sandwiches; seventh, to provide means for uniformly spreading an edible constituent element of the sandwich; eighth, to provide a machine of this class in which the person desiring a sandwich can set and operate the machine to make and 35 deliver various sandwiches as desired; tenth, to provide means for providing a sandwich 40 wrapper; eleventh, to provide a machine of this class in which the food stuffs making up the sandwiches may readily be changed or replaced; twelfth, to provide a machine of this class which will make sandwiches and 45 their constituent elements of uniform thickness; thirteenth, to provide a machine of this class which will reduce to a minimum the waste in connection with the making of sandwiches; fourteenth, to provide a machine 50 of this class in which the driving

mechanism is separated from the sandwich preparing and delivering mechanism; fifteenth, to provide a machine of this class in which all of the parts are readily accessible to authorized persons; sixteenth, to provide 55 a machine of this class with novel means for selecting the filler for the various sandwiches; seventeenth, to provide a machine of this class with novel means for regulating the different thicknesses of the constituent 60 elements of the various sandwiches; eighteenth, to provide a machine of this class which may be readily adjusted to cut various thicknesses of the constituent elements of the sandwich; nineteenth, to provide 65 novel means for slicing the food stuffs making up the sandwiches; twentieth, to provide means for receiving the various prepared elements constituting the sandwich and combining the same; twenty-first, to provide 70 a novelly constructed sandwich preparing, displaying and vending machine and twenty-second, to provide a machine of this class which is very simple and economical 75 of construction proportionate to its functions, durable, efficient and which will not readily deteriorate or get out of order.

With these and other objects in view as will appear hereinafter our invention consists of certain novel features of construction, combination and arrangement of parts and portions as will be hereinafter described in detail and particularly set forth in the appended claims, reference being had to the accompanying drawings and to the 85 characters of reference thereon which form a part of this application in which:

Figure 1 is a top or plan view of our machine with the cover and frame partly broken away and in section to facilitate the 90 illustration; Fig. 2 is a front elevational view thereof; Fig. 3 is a sectional view taken through 3-3 of Fig. 2 with the food containers and carrier plate removed and showing two food containers by dotted lines; Fig. 4 is a sectional elevational view taken through 4-4 of Fig. 1 showing the arrangement of the driving mechanism; Fig. 5 is an upside down sectional view taken through 95 5-5 of Fig. 6 showing the general arrangement of the driving mechanism; Fig. 6 is a 100

ment of the driving mechanism, coin receiving apparatus, switch, buttering device and sandwich receiving container; Fig. 6 is a sectional view taken through 6—6 of Fig. 1 with the glass enclosure removed and showing parts in elevation to facilitate the illustration; Fig. 7 is an enlarged fragmentary sectional view taken above the guide plate 1 showing the cam mechanism, knife, controller plate and the like and showing one of the containers fragmentarily by dotted lines; Fig. 8 is a front elevational view thereof with the glass and lower enclosures removed, parts being broken away to facilitate the illustration and showing by dotted lines the withdrawn position of the sandwich slice receiving fingers; Fig. 9 is a fragmentary sectional view taken through 9—9 of Fig. 7; Fig. 10 is a fragmentary sectional view taken through 10—10 of Fig. 7; Fig. 11 is an enlarged fragmentary sectional view taken through 11—11 of Fig. 1 showing the buttering device; Fig. 12 is a fragmentary sectional view taken through 12—12 of Fig. 11, parts being broken away to facilitate the illustration; Fig. 13 is an enlarged fragmentary sectional elevational view taken through 13—13 of Fig. 5; Fig. 14 is a fragmentary upside down plan view taken at 14—14 of Fig. 13 showing the arrangement of the switch members and Fig. 15 is a fragmentary sectional view taken through 15—15 of Fig. 13 showing the switch tripping cam on the container in position after having tripped the switch release plunger and showing by dotted lines the relative position of both before tripping the latter.

Like characters of reference refer to similar parts and portions throughout the several views of the drawings.

The guide plate 1, base plate 2, spacers 3, stationary frame members 4, base 5, annular member 6, supporting members 7, frame members 8, glass plates 9, cover 10, hand-hole cover 11, cover knob 12, cover bolts 13, collapsible enclosures 14 and 15, fabric mounting 16, hinges 17, latch members 18 and 19, motor 20, conductors 21, switch 22, worm pinion 23, coupling 24, worm gear 25, gear case 26, shaft 27, gear 28, pinion shaft 29, ball and thrust bearing 30, bushing 31, knife supporting member 32, eccentric disc 33, ball bearings 34, guides 35, flanged collar 36, thrust bearing 37, spur gear 38, container carrier plate 39, food containers 40, 41, 42, 43, 44 and 45, clips 46, sprocket wheels 47 and 48, chain 49, shaft 50, pinion 51, cam supporting members 52 and 53, bread weights 54, cables 55, supports 56, filler weights 57, non-corrosive plates 58, shank members 59, takeup plates 60, adjusting nuts 61, clips 62, fiber trimming bar 63, knife 64, knife guide member 65, cams 66 and 67, slice regulating fingers 68 and 69,

slice regulating plate 70, collar 71, shaft 72, journal 73, collar 74, key 75, collar 76, handle 77, spring 78, index plate 79, ratchet 80, pawl 81, spring 82, bevel gears 83 and 84, shaft 85, journals 86, fingers 87, sandwich receiving container 88, bolt 89, spring 90, arm 91, weight 92, cams 93, adjustable finger member 94, shaft 95, bracket 96, journal 97, ratchet wheel 98, collar 99, bevel gears 100 and 101, spindle 102, finger operating lever 103, sandwich slice receiving fingers 104 and 105, bifurcated lever 106, lever 107, bracket 108, spring 109, spring casing 110, pawl 111, spring 112, finger 113, plate 114, sandwich delivery plate 115, delivery lever 116, spring 117, door 118, link 119, paper roll 120, bracket 121, cutting member 122, spring 123, bracket 124, coin receiving member 125, coin 126, plunger 127, screw 128, spring 129, plunger 130, rod 131, coupling 132, bracket 133, spring 134, plunger 135, plunger casing 136, spring 137, cam 138, coin box 139, frame 140, cam 141, roller 142, spindle 143, journal 144, gear 145, compression spring 146, spread container 147, cover 148, gear 149, pin 150, screw 151, and plunger 152 constitute the principal parts and portions of our sandwich preparing, displaying and vending machine.

Our machine is preferably made up of two separate compartments, A, the food display compartment, and B, the compartment housing the driving mechanism and the like and are separated by the guide plate 1. Said guide plate is supported by the base plate 2 and spaced apart therefrom by the spacer members 3 and the stationary frame members 4. Said base plate 2 is mounted on a base 5 preferably of wood and secured thereto in any convenient manner. The plate 1 is surrounded by the annular member 6 adapted to support the upper frame work and is secured to the plate 1 by the supporting members 7 secured to the under sides of said plate at its periphery and said annular member and serving also as a sill for the upper edges of the collapsible enclosure. Mounted on the upper side of said annular member and the plate 1 near the edge thereof are the frame members 8 adapted to support the glass plates 9 forming a panel-like enclosure for the food display compartment A. Mounted on the upper portion of said frame 8 is the cover 10, which may be readily removed when desired. Said cover 10 is provided with a hand-hole 10^a so that the food compartments may be readily replenished therethrough. A hand-hole cover 11 is provided to cover the opening 10^a in said cover 10. A knob 12 is provided on said hand-hole cover and extends therethrough. Bolt members 13 are pivotally mounted on the inwardly extending end of said knob 12 adapted to engage

the under side of the cover 10 at the edge of the opening by turning the knob 12 slightly as shown best in Fig. 1 of the drawings. Clips 13^a are provided on the under side of said covers 11 to guide the bolts 13. The collapsible enclosures 14 and 15 enclosing the compartment B consist of substantially narrow members 14^a and 15^a secured together by the fabric mounting 16 secured to the back of said members in any convenient manner, thus permitting said collapsible enclosures 14 and 15 to be readily removed and rolled up as desired. Said enclosures 14 and 15 are hinged at their one end to the stationary frame members 4 by the hinges 17 and are secured together at their free ends by the latch members 18 and 19 as shown best in Fig. 2 of the drawings.

Mounted in the enclosure B, preferably on the under side of the guide plate 1, is a motor 20 connected to a source of electrical energy by the conductors 21 through the switch 22, as will be described later. Said motor 20 is directly connected to a worm 23 through the flexible coupling 24 connecting the shaft of said worm and said motor. Said worm 23 engages a worm gear 25, both of which are mounted in a gear casing 26 supported on legs 26^a secured to the lower plate 2 as shown best in Figs. 5 and 6 of the drawings. The worm gear 25 is provided with a shaft 27 journaled in said gear case and the plates 1 and 2. A gear 28 is secured on the shaft 27 above said gear case adapted to engage a pinion 29^a secured integrally to the vertical shaft 29 located and journaled centrally in the plates 1 and 2. Said shaft 29 is provided at its lower end with a combination thrust and lateral ball bearing 30 adapted to take care of the downward and lateral action of the shaft. A bushing 31 is provided in the plate 1 to receive the enlarged portion 29^b of the shaft 29 and extends above said plate serving as a stop for the knife supporting member 32. A disc 33 is mounted eccentrically on the shaft 29 shouldered against the enlarged portion thereof above the plate 1 and the knife supporting member adapted to engage 50 at its periphery the ball bearings 34 mounted on either end of the knife supporting member 32 for imparting to the knife mounted on said knife supporting member a reciprocating motion. Said knife supporting member 32 is guided and retained against the upper surface of the plate 1 in its reciprocating movement by the guide 35 secured to the upper surface of the plate 1 on either side of the knife supporting member. A 55 collar 36 is mounted on the upper reduced portion of the shaft 29, adjustable longitudinally thereon. Mounted on said shaft above the collar 36 is the thrust bearing 37 adapted to carry the more slowly moving 60 gear 38 and container carrier plate 39 which

are secured together. Said carrier plate extends beyond the periphery of the gear 38 and carries a plurality of food containers 40, 41, 42, 43, 44 and 45 which are secured to said plate by means of clips 46. 70

Secured at the lower end of the shaft 27 is a sprocket wheel 47 imparting its motion to the sprocket wheel 48 by means of the chain 49. Said sprocket wheel 48 is supported by the shaft 50 extending between 75 the plates 1 and 2 and journaled in the same. Said shaft 50 extends above the upper plate 1 and is provided at said upper end with a pinion 51 secured thereto adapted to engage the gear 38 secured to the under side of the carrier plate 39 and mounted on the shaft 29 as shown best in Figs. 5 and 6 of the drawings. The containers are secured to the container carrier plate 39 in an annular row 80 in spaced relation with each other and extend outwardly therefrom. The containers 40 and 45, as shown best in Fig. 1 of the drawings, are adapted for bread containers whereas the containers 41, 42, 43 and 44 are adapted to receive the filler portions of the sandwiches. Said containers are further supported and reinforced with each other by means of the slotted cam supports 52 and 53 extending between the containers and variously spaced vertically with relation to 85 each other. Suspended in each of the bread containers 40 and 45 are the weights 54 provided at their lower sides with downwardly projecting lugs 54^a. Said weights are secured to the cables 55 which pass through 90 the holes 56^a in the supports 56 and are provided at their upper ends with loops 55^a to limit the downward movement of the weights 54. Said weight cables 55 are long 95 enough so that the last slice of bread in the 100 container can be cut and used in making the sandwiches. It will be here noted that the loaves of bread used in making the sandwiches are considerably longer than the 105 depth of the container and therefore project considerably above the top of the same 110 as shown by dotted lines in Fig. 2 of the drawings; that the weights 54 are held in position on said loaves by the lugs 54^a on 115 the lower side of said weights; that the supports 56 rest on said weights and that the cables 55, being flexible, will not interfere with the cover 10 of the compartment A but will be permitted to dangle at the sides of the loaves until the same have been used 120 sufficiently so that the loaves and the members 54, 55 and 56 will resume the position as shown in Fig. 6 of the drawings. The sandwich filler containers 41, 42, 43 and 44 125 are provided with weights 57 which are provided with non-corrosive plates 58 secured to said weight 57. Said weights are suspended and guided by the supports 56 resting on the upper edges of said containers by 130 the shank members 59 secured to said

weights and passing through similar holes in the supports 56 as previously described. Said shank members 59 when suspended from the support 56 by the loops 59^a at 5 their upper ends are of such length that the plates on the under side of the weights 57 will not interfere with the cutting edge of the knife but will permit the last portion of the filler in said container to be used in 10 making the sandwiches.

In order to take care of any variation in the cross section of the loaves of bread used in connection with our machine we have provided an adjustable takeup plate 60 15 within the bread containers on the leading side thereof. Said plates are provided with screws 60^a secured thereto adapted to be adjusted by the adjusting nuts 61 revolutely mounted in the clips 62 secured to said 20 container.

All of the revolving food containers are spaced above the plate and above the reciprocating knife to prevent any damage to the latter member and a substantially soft 25 material, preferably a fiber trimmed bar 63, is secured to the following edge of each container slightly above the cutting edge of the knife so that the food cut in said containers will be sliced and trimmed neatly throughout its lower exposed surface.

The knife 64 is secured at one end to the laterally reciprocating knife supporting member 32 by the screws 64^a and is reciprocably mounted at its free end in the knife 35 guiding member 65 which is secured to the upper face of the plate 1 by the screws 65^a.

It will be here noted that in making sandwiches the bread enclosing the filler thereof is preferably made from slices of uniform 40 thickness but that the thickness of the fillers of said sandwiches vary in accordance with the kind of filler and we have provided means for regulating the slicing and the thicknesses of the various fillers and also 45 a means for selecting the various fillers or selecting the sandwich desired. The cam supporting member 52 reinforcing the food containers near their lower ends are provided with slots 52^a adapted to receive there- 50 in the cams 66 which are tangentially adjustable on said support and are all adapted to engage the same pawl. The cam supporting members 53 are similarly mounted on the various containers but variously 55 spaced from the supports 52 adapted to receive in their slotted portion the tangentially and radially adjustable cams 67. Said cams 67 are positioned above and behind the cam 66 permitting the latter cam to en- 60 gage its tripping pawl before the cams 67 engage the slice regulating fingers 68 and 69. The slice regulating finger 68 is adapted to be engaged by the cam 67 between the containers 44 and 45 for setting the slice regulating plate 70 with respect to the cut-

ting edge of the knife 64 for slicing the bread in the containers 45 and 40 respectively. It will be here noted that since the slices of bread are preferably made of the same thickness and since the bread container 40 follows the bread container 45 in a path around the shaft 29 it is not necessary to reset the slice regulating plate between the two bread containers and therefore the cams 66 and 67 are eliminated on the supports 52 and 53 between the two said containers. The remaining four radially adjustable cams 67 are variously spaced vertically and correspond in height with the various positions of the finger 69 as shown by solid and dotted lines in Fig. 10 of the drawings. The finger 68 is secured in the collar 71 which is fixedly secured near the top of the vertical shaft 72 which is revolutely mounted in the journal 73 secured to the top face of the plate 1, as shown best in Figs. 7, 8 and 10 of the drawings. The finger 69 is secured in the collar 74 which is shiftably mounted on said shaft, a key being provided in said collar adapted to ride in the longitudinal key seat 72^a in said shaft. Said collars 74 is reduced at its lower end 74^a to receive the collar 76 which is revolutely mounted thereon and riveted in place as shown in Fig. 10 of the drawings. Said collar 76 is provided with a handle 77 extending outwardly therefrom adapted to raise and lower the finger 69 as desired. The reduced portion 77^a of said handle also extends through slots 79^a and 79^b of the index plate 79 which is secured at the front of the machine to the plate 1, a portion of the glass plate behind said index plate being cut away. The vertical slot 79^b in said index plate permits the reduced portion of the handle 77 to be shifted vertically therein into the various cross slots 79^a, communicating with said vertical slot, which permit the handle and therefore the fingers 69 to be held in certain relative positions corresponding with the vertical positions of the four radially adjustable cams 67 before mentioned. Said handle 77 is retained in said cross slots by the tension spring 78 secured to said handle and said finger 69. 105 Mounted on the shaft 72 is the ratchet 80 secured to the same above the journal 73. The pawl 81, adapted to be engaged and tripped by the cams 66, is pivotally mounted on the boss 73^a secured to the base of 110 said journal and is adapted to engage the ratchet 80 retaining the shaft 73 in its revolved position when shifted by the cams 67 until tripped by the cams 66. A spring 82 is mounted on the boss 73^a, secured there- 115 to at one end and secured at its other end to said pawl adapted to hold the same in engagement with said ratchet. A bevel gear 83 is mounted on the lower end of the shaft 72 extending through the plate 1 and en- 120 125

gages with a smaller bevel gear 84 mounted on the shaft 85 which is revolubly mounted in the journals 86 secured on the under side of the plate 1 by screws 86^a. Secured in 5 this shaft 85 are the curved fingers 87 extending outwardly therefrom through the slots 88^a of the sandwich receiving container 88 and upwardly through the plate 1 adapted to support the free edge of the slice 10 regulating plate 70 and regulate the movements of the same as previously described and as shown best in Figs. 7, 8 and 10 of the drawings. Said regulating plate 70 is a comparatively flexible plate and is pivotal- 15 ly mounted at its other edge in the sub-recess 1^b in the circular guide channel 1^c of the plate 1 and is held in a flexible position flush with the bottom of said channel by the bolts 89 countersunk in the top 20 surface of said regulating plate and which extend downwardly through the plate 1 and are held downwardly by the springs 90 interposed between the nut of the bolt and the underside of the plate 1. The shaft 25 85 is provided with an arm 91 extending outwardly at a right angle therefrom on the opposite side from said curved fingers 87. Said arm is provided with an adjustable weight 92 mounted thereon adapted to 30 keep the regulating plate 70 flush with the edge of the knife 64, the upward position of which plate is limited by the slots 88^a in the receiving container 88 through which the fingers 87 extend.

35 In order to receive the constituent elements of a sandwich after they are sliced and combine the same to form a sandwich we have provided finger and lever means operative directly by the position on the various 40 containers of the cams 93 secured to the outside of said containers. Said cams 93 are adapted to engage an adjustable finger member 94 mounted on the shaft 95 which is revolubly mounted in the bracket 96 at its upper 45 end, in the plate 1 at its middle portion and in the bracket 97 at its lower end, which bracket 97 is secured to the plate 2. Mounted on said shaft on the upper face of the plate 1 is the ratchet wheel 98 which is se- 50 cured to said shaft. A collar 99 is secured on said shaft below the plate 1 positioning said shaft vertically. Mounted near the lower end of the shaft 95 is the beveled gear 100 which engages a smaller beveled gear 101 mounted on the spindle 102 which is revolubly mounted in the journal 97. Mounted on the other end of the spindle 102 is a finger operating lever 103 near the upper end of which are mounted two sets of 55 fingers 104 and 105 both of which are pivotally mounted in the lever 103. The lower fingers 104 are guided by holes 88^b in the sandwich receiving container 88 and are adapted to receive the slices as they leave the knife and on which said slices rest until said fingers are withdrawn, as shown by dotted lines in Fig. 8 of the drawings. The fingers 105 are mounted above the finger 104 and intermediate its individual members and are somewhat pointed and curved upwardly at 70 their free ends extending beyond the ends of the lower fingers and near the cutting edge of the knife adapted to guide the various slices from the knife to the fingers 104. The fingers 105 are guided laterally in the slots 75 88^c of the sandwich receiving container and are governed in their vertical movements by the bifurcated lever member 106 which is pivotally mounted near the lower portion of the finger operating lever 103, as shown best 80 in Figs. 8 and 9 of the drawings. Another lever member 107 provided with a roller 107^a at its free end is pivotally mounted in the bracket 108 secured to the under side of the plate 1. A spring 107^b is interposed be- 85 tween the under side of the plate 1 and the lever 107 adapted to force the fingers 105 in engagement with the bifurcated guide lever 106 by keeping the rollers 107^a on the lever 107 in engagement with the fingers 105. The 90 lever 107 is also guided in its circular motion by the bifurcated portion of the lever 106. It will be seen from the description and in Fig. 8 of the drawings that the fingers after having received the slice will be rapidly withdrawn permitting the upper fingers 105 to move downwardly between the finger 104. It will also be seen that the portion of the slice leaving the fingers first will move downwardly more rapidly by the force of gravity and that the other end leaving the finger 104 last will be forced rapidly downwardly by the fingers 105 passing between the members 104, thus permitting them to drop down in the sandwich receiving container in a sub- 95 stantially flat position. In order to keep the fingers 104 and 105 in a position ready to receive the slices as they are cut by the knife 64 there is provided a spiral spring 109, the one end of which is secured to the finger op- 100 erating lever 103 and the other end of which is secured in the spring casing 110, which is secured to the plate 2 at any convenient place in line with the rotation of the lever 103. A pawl 111 is pivotally mounted on the top 105 face of the plate 1 and secured thereto by the screw 111^a adapted to engage the ratchet 98 and prevent the spring 109 returning the fingers 104 and 105 immediately to their initial receiving positions and give the va- 110 rious slices sufficient time to leave said fingers and to drop down in the sandwich receiving containers in the proper manner. A spring 112 mounted on the screw 111^a, one 115 end of which is secured to said screw and the other end to said pawl, is adapted to retain the pawl 111 in engagement with the ratchet 98. A finger 113 is secured to the boss 111^b of the pawl 111 at approximately the same ele- 120 vation from the plate 1 as the adjustable

finger 94 and is adapted to be engaged by the cam 93 disengaging the pawl 111 from the ratchet wheel 98, however after the various slices cut by the knife are given sufficient time to drop down in the container 88.

5 A plate 114 is provided behind the knife 64 above the circular channel 1^a of the plate 1 and secured to said plate adapted to lower the food stuffs in the various containers gradually into the circular channel after leaving the knife.

10 The sandwich receiving container 88 is secured to the under side of the plate 1 by the angle clips 88^a, under the path of the 15 various food containers and under the knife, the plate 1 being provided with an opening 1^a at this place above the sandwich receiving container. Said sandwich receiving container is provided with a pivoted sandwich delivery plate 115 which is pivotally mounted at its rear end in the lugs 88^b and which plate is provided with a downwardly extended apron portion 115^a to conceal the driving mechanism. Mounted on the under side of the plate 115 is the outwardly extending lever 116 which readily permits the operator to lower the bottom of the container and remove the sandwiches therefrom. A spring 117 is secured to the container 88 and to the pivoted bottom plate 115 adapted to keep said plate in engagement with the said container. Said container is further provided with a door 118 which is pivotally mounted on the front portion thereof. Said door is provided with an arm portion secured thereto, the free end of which is pivotally mounted to a link 119, the other end of which is pivotally mounted at the edge of the plate 115 in such a manner that the plate 115 and the door 118 operate and open simultaneously by the downward movement of the lever 116 as shown best by dotted lines in Fig. 6 of the drawings.

45 A roll of paper 120 is revolvably mounted in the bracket 121 under the sandwich receiving container adapted to provide means for wrapping the sandwiches as they are taken from the receiving container 88. A 50 roller 121^a and a spring 121^b are mounted in a slotted extended arm of said bracket 121 adapted to bear against the roll of paper 120 to provide tension thereon. The bottom plate 115 of the sandwich receiving 55 container is provided with a slot 115^b adapted to receive therethrough the paper which extends along the plate a short distance under the cutting member 122 which is pivotally mounted in lugs 115^c extending upwardly from the plate 115. A spring 123 is also mounted on said lug adapted to bear against the said cutting member 122 which bears against the plate 115, thus retaining the end of the paper in said container and

permitting the same to be severed as desired.

To automatically vend and make the sandwiches we have provided a coin operated switch mechanism and an automatic releasing device as is described herewith. 70 The bracket 124 is secured to the under side of the plate 1 and extends forwardly in front of the enclosures 14 and 15 which separate at this place. The coin receiving member 125 is secured to the forward end 75 of said bracket which is provided with a slot 125^a adapted to receive therein a coin 126 of a predetermined size. Said member 125 is adapted to receive the reciprocable plunger 127 which is retained therein by 80 the screw 128 shiftable in the slot 125^b of the coin receiving member 125. A spring 129 is interposed between the shoulders of the members 125 and 127 adapted to force said plunger 127 outwardly. The bracket 124 is provided on its downwardly extending leg with an inwardly extending cylindrical portion 124^a having a cylindrical recess slightly larger than the diameter of the coin 126.

A plunger member 130 is reciprocably mounted in the cylindrical portion of said bracket and is provided with a rod 130^a secured thereto extending through said cylindrical portion toward the switch member 22. The outer portion of the plunger 130 is adapted to receive the reduced portion 127^a of the plunger 127 when the same is forced inwardly, providing no coin has been dropped in the slot 125^a of the member 125. Thus the plunger 130 will remain in the position shown in Fig. 13 of the drawings and, therefore, no contact of the switch members is made. If, however, a coin is dropped into the slot 125^a and the plunger 105 127 is forced inwardly, the coin 126 will bear against the shoulders 130^a of the plunger member 130 forcing said plunger member inwardly and making an electrical contact by said switch member. The rod 110 130^a of the plunger 130 is connected to the rod 131 and insulated therefrom by the insulating coupling 132. Said rod 131 is reciprocably mounted in the insulating bracket 133 which is secured to the under side of the plate 1 by screws 133^a. A spring 134 is interposed between the coupling 132 and the bracket 133 tending to force the rod 130^a and therefore the plunger 130 outwardly and tending to keep the 115 switch members apart and breaking the electrical contact. The switch 22 consists of two switch members 22^a spaced from each other and mounted on the insulating bracket 133 and connected to the conductors 21.

The rod 121 is provided at its free end with a flattened portion 131^a to which is secured the circuit breaking member 22^b.

which is adapted to engage each of the members 22^a completing the electrical circuit. The rod 130^c is provided with a notch 130^c at the under side thereof adapted to engage 5 a raised portion 135^a in the slotted plunger 135 which is reciprocably mounted in the plunger casing 136 secured to the under side of the plate 1 and preferably in the positions shown in Figs. 1, 3 and 13, of the 10 drawings. The raised portion 135^a of said plunger is kept in constant engagement with the rod 135^a by a spring 137 interposed between the lower end of said plunger and said plunger casing so that when the plunger 130 is forced inwardly, the raised portion 135^a of the plunger 135 will engage the notch 130^c and thus keep the electrical circuit closed. Said plunger 135 extends through and above the plate 1 adapted to 20 be engaged by the cam 138 secured near the lower edge of the inside face of the food container 45, as shown best in Figs. 13 and 15 of the drawings. Said cam engages and forces said plunger downwardly only after 25 a complete revolution of the various containers and after a sandwich has been made. The relative positions of the cam and the plunger before tripping or releasing are shown by dotted lines in Fig. 15 of the drawings. The cylindrical portion 124^a of the bracket 124 is provided at its under side with a slot 124^b to permit the coin 126 to drop therethrough after the plunger 130 has been forced inwardly and an electrical contact made. A coin box 139 is mounted in 30 a frame 140 secured to the base plate 2 and is connected to the slot 124^b by the chute 140^a secured at the upper end to the bracket 124 and permits the coin to drop through 40 said slot 124^b through the chute 140^a into the coin box 139, as shown best in Fig. 13 of the drawings.

To spread butter or other plastic food stuff on the bread we have provided automatic pressure means, as shown best in Figs. 45 11 and 12 of the drawings. Since it is desired that a spread be applied only to the last slice of bread in making up the sandwich, the containers 45 contributing the 50 last slice of bread to said sandwich is provided with a cam 141 secured thereto near its lower outer edge. Said cam is circular in shape at its engaging edge and is slightly longer at said edge than the width of a slice 55 of bread. Said cam 141 is adapted to engage a rubber tired roller 142, which is mounted on a vertical spindle 143 which is revolubly and shiftably mounted in the journal 144 secured to the under side of the 60 plate 1. Said spindle 143 is provided at its lower end with a shrouded gear 145 and is held in its downward position by a spring 146 interposed between the journal 144 and the gear 145. The spread container con-

sists of a container member 147 provided 65 at its upper end with a dovetailed flange portion 147^a adapted to be shifted radially relatively to the plate 1 in a similarly shaped channel 1^d provided therein. The upper face of said container is flush with 70 the bottom of the circular channel 1^a of the plate 1 and is provided in said upper portion with a longitudinal slot 147^b through which the spread is forced and applied to the bread. Said container is provided at 75 its lower end with a cover 148 secured thereto preferably as shown. Said cover 148 is provided with a downwardly extending boss 148^a in which is revolubly mounted the hub of the gear 149 adapted to engage the 80 gear 145. Said gear is retained in said boss 148^a by the pin 150 on which the hub of the gear 149 rides. The gear 149 is internally threaded adapted to receive the screw 151 at the upper or inner end of which is 85 mounted the plunger plate 152 adapted to compress the spread in said container and force the same through the slot 147^b provided therein at its upper end.

It will be here noted that as the cam 141 engages the roller 142 the same is rotated which in turn rotates the gear 149 engaging the gear 145; that the gear being revolubly mounted and internally threaded will force the screw 151 mounted therein upwardly. 90 It will be further noted that if the spread container 147 is to be refilled the enclosure 14 is pulled up and the gear 145 is raised up disengaging the same from the gear 149 and permitting the container and gear to 95 be readily withdrawn by means of the channel 1^a in the plate 1 and refilled.

Though we have shown and described a particular construction, combination and arrangement of parts and portions we do 100 not wish to be limited to this particular construction, combination and arrangement but desire to include in the scope of our invention the construction, combination and arrangement substantially as set forth in 110 the appended claims.

It is obvious that when the handle 77 is inserted in a certain cross notch in the index plate the finger 69 will be positioned in the path of any of the containers 41, 42, 43 or 115 44 containing the fillers for the various sandwiches; that when a coin of a certain size is inserted in the slot of the member 125 and the plunger 127 forced inwardly an electrical contact is made starting the motor 120 20; that the plunger 135 will engage the notch 130^c in the plunger rod 130^a keeping the switch closed; that the knife 64 will be set in motion as previously described; that the carrier plate 39 will be revolved bringing the various food containers consecutively over said knife; that the adjustable cam 125 between the containers 44 and 45 has previ-

ously set the regulating plate 70 to cut a slice of bread a certain thickness; that as the container 40 moves over said knife the slice of bread is cut, and received by the separate fingers 104 and 105 and dropped into the receiving container; that as the next cam 66 engages the pawl 81 the regulating plate is forced upwardly flush with the edge of the knife; that prior to the 10 movement of any one of the following four containers depending on the position of the regulating handle 77, the regulating plate 70 is lowered, permitting a slice of the filler to be cut and retained by the fingers 15 within the sandwich receiving containers; that as the final food container 45 nears the knife the cam 141 secured thereto engages the roller 142 forcing the spread through the slot 147^d of the spread container; that the adjustable cam between the 20 containers 44 and 45 will engage the finger 68 lowering the regulating plate to permit the knife to cut another slice of bread spread on one side, to be received by the 25 fingers in the receiving container and to be dropped on the other elements of the sandwich; that by forcing the lever 116 downwardly the prepared sandwich may be removed; that we have provided wrapper 30 means for the prepared sandwich; and that we have provided an efficient, automatic and sanitary machine for preparing and vending sandwiches.

Having thus described our invention what 35 we claim as new and desire to secure by Letters Patent is:

1. In a machine of the class described, a frame, a motor mounted on said frame, a shaft revolvably mounted in said frame, gear 40 means connecting said motor to said shaft, containers mounted on said shaft, cutting means mounted on said frame, positioned contiguous to the path of said containers and connected to said gear means, slice regulating means positioned adjacent said cutting means, and a food receiving container secured to said frame contiguous to said cutting means.

2. In a machine of the class described, a 50 frame, a motor mounted on said frame, a coin regulated switch means communicating with said motor, a shaft revolvably mounted in said frame, gear means connecting said motor to said shaft, containers mounted on 55 said shaft, cutting means mounted on said frame, positioned contiguous to the path of said containers and connected to said gear means, slice regulating means positioned adjacent said cutting means, and a food receiving container secured to said frame contiguous to said cutting means.

3. In a machine of the class described, a frame, a motor mounted on said frame, a shaft revolvably mounted in said frame,

gear means connecting said motor to said 65 shaft, containers mounted on said shaft, cutting means mounted on said frame, positioned contiguous to the path of said containers and connected to said gear means, selecting means including fingers positioned 70 in the path of said containers and lever means for variously positioning said fingers, slice regulating means positioned adjacent said cutting means, and a food receiving container secured to said frame contiguous 75 to said cutting means.

4. In a machine of the class described, a frame, a motor mounted on said frame, a shaft revolvably mounted in said frame, gear means connecting said motor to said shaft, 80 containers mounted on said shaft, cutting means mounted on said frame, positioned contiguous to the path of said containers and connected to said gear means, slice regulating means positioned adjacent said cutting means, and slice receiving and assembling means communicating with said cutting means.

5. In a machine of the class described, a frame, a motor mounted on said frame, a shaft revolvably mounted in said frame, gear means connecting said motor to said shaft, containers mounted on said shaft, cutting means mounted on said frame, positioned contiguous to the path of said containers and connected to said gear means, slice regulating means positioned adjacent said cutting means, a food receiving container secured to said frame contiguous to said cutting means, and a wrapper distributing 100 means for wrapping said sliced food.

6. In a machine of the class described, a frame, a motor mounted on said frame, a shaft revolvably mounted in said frame, gear means connecting said motor to said shaft, 105 containers mounted on said shaft, cutting means mounted on said frame, positioned contiguous to the path of said containers and connected to said gear means, slice regulating means positioned adjacent said cutting 110 means, means for spreading an edible on said slices, and a food receiving container secured to said frame contiguous to said cutting means.

7. In a machine of the class described, a 115 frame, a motor mounted on said frame, a shaft revolvably mounted in said frame, gear means connecting said motor to said shaft, containers mounted on said shaft, cutting means mounted on said frame, positioned 120 contiguous to the path of said containers and connected to said gear means, selecting means including fingers positioned in the path of said containers and lever means for variously positioning said fingers, slice regulating means positioned adjacent said cutting means, pressure actuated means for spreading an edible on the slices, and a food 125

- receiving container secured to said frame contiguous to said cutting means.
8. In a machine of the class described, a frame, a motor mounted on said frame, a shaft revolubly mounted in said frame, gear means connecting said motor to said shaft, containers mounted on said shaft, cutting means mounted on said frame, positioned contiguous to the path of said containers and connected to said gear means, selecting means including cams secured to said containers, fingers positioned in the path of said cams, lever means for variously positioning said fingers, automatic slice regulating means positioned adjacent said cutting means, pressure actuated means for spreading an edible on said slices, and a food receiving container secured to said frame contiguous to said cutting means.
9. In a machine of the class described, a frame, a motor mounted on said frame, a coin regulated switch means communicating with said motor, a shaft revolubly mounted in said frame, gear means connecting said motor to said shaft, containers mounted on said shaft, cutting means mounted on said frame, positioned contiguous to the path of said containers and connected to said gear means, food selecting means including fingers positioned in the path of said containers and manually operated lever means for variously positioning fingers, adjustable slice regulating means communicating with said selecting means and positioned adjacent said cutting means, and a food receiving container secured to said frame contiguous to said cutting means.
10. In a machine of the class described, a frame, a motor mounted on said frame, a coin regulated switch means communicating with said motor, a shaft revolubly mounted in said frame, gear means connecting said motor to said shaft, containers mounted on said shaft, cutting means mounted on said frame, positioned contiguous to the path of said containers and connected to said gear means, food selecting means including fingers positioned in the path of said containers and manually operated lever means for variously positioning fingers, adjustable slice regulating means communicating with said selecting means and positioned adjacent said cutting means, and a food receiving container secured to said frame contiguous to said cutting means.
11. In a machine of the class described, a frame, a motor mounted on said frame, a coin regulated switch means communicating with said motor, a shaft revolubly mounted in said frame, gear means connecting said motor to said shaft, containers mounted on said shaft, cutting means mounted on said frame, positioned contiguous to the path of said containers and connected to said gear means, food selecting means including fingers positioned in the path of said containers and manually operated lever means for variously positioning fingers, adjustable slice regulating means communicating with said selecting means and positioned adjacent said cutting means, and a food receiving container secured to the other side of said plate from said containers contiguous to said cutting means.
12. In a machine of the class described, a frame, a motor mounted on said frame, a coin regulated switch means communicating with said motor, a shaft revolubly mounted in said frame, gear means connecting said motor to said shaft, containers mounted on said shaft, cutting means mounted on said frame, positioned contiguous to the path of said containers and connected to said gear means, food selecting means including fingers positioned in the path of said containers and manually operated lever means for variously positioning said fingers, adjustable slice regulating means communicating with said selecting means and positioned adjacent said cutting means, a food receiving container secured to said frame contiguous to said cutting means, and a paper means for wrapping said sliced food.
13. In a machine of the class described, a readily accessible enclosure, provided with transparent panels, a motor mounted in said enclosure, a shaft revolubly mounted in said enclosure, a gear means connecting said motor to said shaft, containers mounted on said shaft, cutting means mounted on said enclosure, positioned contiguous to the path of said containers and connected to said gear means, slice regulating means positioned adjacent said cutting means, and a food receiving container secured to said enclosure contiguous to said cutting means.
14. In a machine of the class described, a supporting plate provided with a channel therein, a transparently paneled enclosure mounted above said plate, a motor mounted on said plate, a shaft revolubly mounted in said plate, gear means connecting said motor to said shaft, containers mounted on said shaft within said paneled enclosure, cutting means mounted on said plate positioned contiguous to the path of said containers and the channel in said plate and connected to said shaft, other shaft and gear means connected with said motor and said containers, adjustable slice regulating means positioned adjacent said cutting means and a food receiving container secured to the other side of said plate from said containers contiguous to said cutting means.
15. In a machine of the class described, a supported plate provided with a channel therein, a transparently paneled enclosure

mounted above said plate, a motor mounted on said plate, a shaft revolubly mounted in said plate, gear means connecting said motor to said shaft, containers mounted on 5 said shaft within said paneled enclosure, cutting means mounted on said plate positioned contiguous to the path of said containers and the channel in said plate and connected to said shaft, other shaft and gear 10 means connected with said motor and said containers, adjustable slice regulating means positioned adjacent said cutting means, a food receiving container secured to the other side of said plate from said containers contiguous 15 to said cutting means, and a coin regulated switch means communicating with said motor.

16. In a machine of the class described, a supporting plate provided with a channel 20 therein, a transparently paneled enclosure mounted above said plate, a motor mounted on said plate, a shaft revolubly mounted in said plate, gear means connecting said motor to said shaft, containers mounted on 25 said shaft within said paneled enclosure, cutting means mounted on said plate positioned contiguous to the path of said containers and the channel in said plate and connected to said shaft, other shaft and gear 30 means connected with said motor and said containers, selecting means including fingers positioned in the path of said containers and manually operated lever means for variously positioning said fingers, adjustable slice regulating means 35 communicating with said selecting means and positioned adjacent said cutting means, a food receiving container secured to the other side of said plate from said containers contiguous to said 40 cutting means, and a coin regulated switch means communicating with said motor.

17. In a machine of the class described, a supported plate provided with a channel 45 therein, a transparently paneled enclosure mounted above said plate, a motor mounted on said plate, a shaft revolubly mounted in said plate, gear means connecting said motor to said shaft, containers mounted on said shaft within said paneled enclosure, cutting 50 means mounted on said plate positioned contiguous to the path of said containers and the channel in said plate and connected to said shaft, other shaft and gear means connected with said motor and said containers, 55 selecting means including fingers positioned in the path of said containers and manual lever means for variously positioning said fingers, adjustable slice regulating means communicating with a food selecting means 60 and positioned adjacent said cutting means, pressure actuated means for spreading an edible on said slices, a food receiving container secured to the other side of said plate from said container contiguous to said cut-

ting means, and a coin regulated switch 65 means communicating with said motor.

18. In a machine of the class described, a supported plate provided with a channel therein, a transparently paneled enclosure mounted above said plate, a motor mounted 70 on said plate, a shaft revolubly mounted in said plate, gear means connecting said motor to said shaft, containers mounted on said shaft within said paneled enclosure, cutting means mounted on said plate positioned contiguous to the path of said containers and the channel in said plate and connected to said shaft, other shaft and gear means connected with said motor and said containers, 75 selecting means including fingers positioned in the path of said containers and manual lever means for variously positioning said fingers, adjustable slice regulating means 80 communicating with a food selecting means and positioned adjacent said cutting means, pressure actuated means for spreading an 85 edible on said slices, slice receiving and assembling means positioned contiguous said cutting means and communicating with said containers.

19. In a machine of the class described, a supported plate provided with a channel therein, a transparently paneled enclosure mounted above said plate, a motor mounted 90 on said plate, a shaft revolubly mounted in said plate, gear means connecting said motor to said shaft, containers mounted on said shaft within said paneled enclosure, cutting means mounted on said plate positioned contiguous to the path of said containers and the channel in said plate and connected to 95 said shaft, other shaft and gear means connected with said motor and said containers, selecting means including fingers positioned in the path of said containers and manually 100 operated lever means for variously positioning said fingers, adjustable slice regulating means communicating with said selecting means and positioned adjacent said cutting means, a food receiving container secured to 110 the other side of said plate from said containers contiguous to said cutting means, a coin regulated switch means communicating with said motor, and a paper distributing 115 means for wrapping said sliced food.

20. In a machine of the class described, a supported plate provided with a channel therein, a transparently paneled enclosure mounted above said plate, a motor mounted 120 on said plate, a shaft revolubly mounted in said plate, gear means connecting said motor to said shaft, containers mounted on said shaft within said paneled enclosure, pressure means supported by said containers for forcing the food therein to ride in the channel provided in said plate, cutting means mounted on said plate positioned contiguous to the path of said containers and the chan-

- nel in said plate and connected to said shaft, other shaft and gear means connected with said motor and said containers, adjustable slice regulating means positioned adjacent 5 said cutting means and a food receiving container secured to the other side of said plate from said containers contiguous to said cutting means.
21. In a machine of the class described, a 10 supported plate provided with a channel therein, a transparently paneled enclosure mounted above said plate, a motor mounted on said plate, a shaft revolubly mounted in said plate, gear means connecting said motor to said shaft, containers mounted on said shaft within said paneled enclosure, cutting means mounted on said plate positioned contiguous to the path of said containers and the channel in said plate and connected to 15 said shaft, other shaft and gear means connected with said motor and said containers, adjustable slice regulating means positioned adjacent said cutting means, a slice receiving and assembling means communicating 20 with said cutting means and a wrapping means operated by said slice receiving means for distributing wrapping for said sliced food.
22. In a machine of the class described, an 25 enclosure frame, a plurality of movable food containers in said frame and a movable cutting means positioned contiguous to the lower sides of said food containers movable simultaneously with the movement of said food containers.
23. In a machine of the class described, an enclosure frame, a plurality of movable food containers in said frame, a cutting means positioned contiguous to the lower 30 sides of said food containers, and means for simultaneously operating said food containers and said cutting means.
24. In a machine of the class described, an enclosure frame, a plurality of movable food containers in said frame, a cutting means positioned contiguous to the lower 35 sides of said food containers, a means for simultaneously operating said food containers and said cutting means and a means for receiving and assembling the food elements from said cutting means.
25. In a machine of the class described, an enclosure frame, a plurality of movable food containers in said frame, a cutting means positioned contiguous to the lower 40 sides of said food containers, means for simultaneously operating said food containers and said cutting means, and means positioned contiguous to said cutting means for receiving and assembling the food elements from said cutting means.
26. In a machine of the class described, an enclosure frame, a plurality of movable food containers in said frame, a cutting 45 means positioned contiguous to the lower sides of said food containers, means for simultaneously operating said food containers and said cutting means, and means positioned contiguous to said cutting means for receiving and assembling the food elements from said cutting means.
27. In a machine of the class described, a casing, a plurality of movable food containers in said casing, a slicing means in the path of said food containers adapted to engage the food in some of said containers with the moving of said food containers, and means manually operated for selecting the food adapted to engage said containers and for positioning said food. 50
28. In a machine of the class described, a casing, a plurality of movable food containers in said casing, a slicing means in the path of said food containers adapted to engage the food in some of said containers, means manually operated for selecting the food adapted to engage said containers and for positioning said food, and finger means positioned contiguous to said slicing means adapted to receive and assemble elements of the food. 55
29. In a machine of the class described, a casing, a plurality of movable food containers in said casing, a slicing means in the path of said food containers adapted to engage the food in some of said containers, means manually operated for selecting the food adapted to engage said containers and for positioning said food, finger means positioned contiguous to said slicing means adapted to receive and assemble elements of the food, and means for discharging said food from said casing. 60
30. In a machine of the class described, a casing, a plurality of movable food containers in said casing, a slicing means in the path of said food containers adapted to engage the food in some of said containers, means manually operated for conducting the food adapted to engage said containers and for positioning said food, finger means positioned contiguous to said slicing means adapted to receive and position elements of the food, means for discharging said food from said casing, and coin operated means for regulating and controlling the movement of said food containers and slicing device and food positioning fingers. 65
31. In a machine of the class described, a casing, a plurality of food containers revolubly mounted in said casing, a slicing means positioned in the path of said containers and adapted to slice a portion from the food in said containers, and finger means 70
- means positioned contiguous to the lower 75 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 80
- means positioned contiguous to the lower 85 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 90
- means positioned contiguous to the lower 95 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 100
- means positioned contiguous to the lower 105 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 110
- means positioned contiguous to the lower 115 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 120
- means positioned contiguous to the lower 125 sides of said food containers, means for simultaneously operating said food containers and said cutting means, means positioned contiguous to said cutting means for receiving and assembling the food elements from said cutting means, and manually operated means adapted to engage said containers for selecting the separate foods in said containers for engagement with said cutting means. 130

contiguous to said slicing means for receiving and positioning different slices of food from said containers.

32. In a machine of the class described, 5 a casing, a plurality of food containers revolvably mounted in said casing, a slicing means positioned in the path of said containers and adapted to slice a portion from the food in said containers, finger 10 means contiguous to said slicing means for

receiving and positioning different slices of food from said containers, and manually operated ratchet, pawl and cam means for positioning the food in the separate containers to be engaged by said slicing means. 15

In testimony whereof, we have hereunto set our hands at San Diego, California, this 3d day of May, 1922.

EDWARD LUX.
JOSEPH W. DOBBINS,
